UNITED STATES PATENT OFFICE.

LOUIS W. REINHARDT, OF WHITMAN, MASSACHUSETTS, ASSIGNOR TO CHARLES S. PIERCE,
OF BROCKTON, MASSACHUSETTS.

BRACKET FOR FEED-GAGES.

No. 902,910.

Specification of Letters Patent.

Patented Nov. 3, 1908.

Application filed February 29, 1908. Serial No. 418,461.

To all whom it may concern:

Be it known that I, LOUIS W. REINHARDT, citizen of the United States, residing at Whitman, in the county of Plymouth and State of Massachusetts, have invented a certain new and useful Improvement in Brackets for Feed-Gages, of which the following is a specification, reference being had therein to the accompanying drawings.

10 My present invention relates to machines for skiving leather of the type which have a rapidly rotating disk by means of which the leather is operated upon. Such machines are well known in this art and an example of 15 them may be seen in the patent to Amazeen, No. 273,931, March 13, 1883. In machines of this kind, it is now usual to guide the leather to the cutting instrumentalities by means of a feed roll and a gage, said gage being made in a variety of shapes. Different feed rolls are frequently provided with working surfaces which are beveled at different angles and to obtain satisfactory operation of the machine it has been found necessary 25 to tilt the gage slightly to compensate for feed rolls of different angles. Heretofore this has been accomplished by putting shims of leather or the like between the gage and the bracket, but for obvious reasons this arrangement is unsatisfactory.

30 My invention has for its object to provide means by which the adjustment of the position of the gage may be quickly and conveniently made for a feed roll of different angles, means being also provided so that the gage may be securely fastened in place when the proper adjustment has been obtained.

35 The invention will be fully understood from the following description taken in connection with the accompanying drawings, and the novel features thereof are pointed out and clearly defined in the claims at the close of this specification.

40 Referring now to the drawings,—Figure 1 is a front elevation of a portion of a skiving machine embodying my invention. Fig. 2 is a view in perspective of the bracket with the supporting plate 16 slightly tilted.

45 In the drawings, the feed roll is indicated at 11 and the gage at 12, the frame of the machine being numbered 13. To the frame 13 of the machine is secured the bracket 14 embodying my invention, the feed gage 12

being secured to the upper surface of the said bracket 14. The bracket 14 consists of a 55 vertical plate 15 to which is pivoted the supporting plate 16 for the feed gage 12. The vertical plate 15 of the bracket 14 is provided with two pairs of lugs 17 and 18, and 19 and 20, while the horizontal plate is provided with a downwardly extending portion 21 which lies between the two pairs of lugs. The downwardly extending portion 21 is pivoted at 22 to the pair of lugs 17 and 18 which is nearest the cutting instrumentalities. At 60 the corresponding point on the other side of the bracket, the downwardly extending portion 21 of the horizontal plate 16 is slotted to receive the screw 23 which is received in holes in the lugs 19 and 20.

65 It will be seen that the horizontal piece 16 may be tilted about the pivot 22 until the feed gage is located in proper position with relation to the feed roll 11 and that then it may be secured firmly in place by tightening 70 the screw 23 and causing the opposing surfaces of the two lugs 19 and 20 to bear upon the corresponding surfaces of the downwardly extending portion 21 of the horizontal piece. It will be seen that this construction 75 affords means of tilting the feed gage so that it may be properly positioned with relation to feed rolls of different angles and when once 80 adjusted may be firmly secured in place so that it is not likely to get out of adjustment. 85

I claim as my invention:

90 In combination with a feed gage, a bracket comprising a member for engagement with the frame of the machine and provided with two pairs of lugs thereon, a second member to support the feed gage and provided with a downwardly extending portion, a pivotal connection engaging one pair of the lugs on the first mentioned member and the downwardly extending portion of the second member, 95 and a screw passing through the other pair of lugs so that the said pair of lugs may be caused to engage said downwardly extending member and lock the said member in position.

100 In testimony whereof I affix my signature, in presence of two witnesses.

LOUIS W. REINHARDT.
